DESIGN FOR A WINDOW VENTILATOR

William Siebels, San Francisco, Calif., assignor
to I. J. Roth, Burlingame, Calif.

Application October 14, 1946, Serial No. 133,950

Term of patent 14 years

(Cl. D62—4)

To all whom it may concern:

Be it known that I, William Siebels, a citizen of the United States, residing at San Francisco, in the county of San Francisco and State of California, have invented a new, original, and ornamental Design for a Window Ventilator, of which the following is a specification, reference being had to the accompanying drawing, forming a part thereof.

Figure 1 is a front view of a window ventilator showing my design;

Figure 2 is a top plan view of the same;

Figure 3 is a rear view of the same;

Figure 4 is an end view of the same; and

Fig. 5 is a sectional view taken on the line 5—5 of Fig. 1.

I claim:

The ornamental design for a window ventilator, substantially as shown.

WILLIAM SIEBELS.
